(57) **CLAIM**

The ornamental design for a suspended ceiling grid runner assembly, as shown and described.

DESCRIPTION

FIG. 1 is a fragmented isometric view, from below, of a suspended ceiling grid runner assembly showing our new design;

FIG. 2 is a fragmented side view thereof taken parallel to a main runner, the opposite view being a mirror image of this view;

FIG. 3 is a fragmented side view thereof taken parallel to a cross runner, the opposite view being a mirror image of this view;

FIG. 4 is a fragmented top plan view thereof; and,

FIG. 5 is a fragmented bottom plan view thereof.
The dotted-line showing in the drawings illustrates environmental matter and forms no part of the claimed design.
